United States Patent

Des. 237,379
Patented Oct. 28, 1975

237,379

BUILDING

Joseph A. Bondurant, 752 Old Dobbin Road,
Lexington, Ky. 40502

Filed May 15, 1973, Ser. No. 360,553

Term of patent 14 years

Int. Cl. D25—03

U.S. Cl. D13—1 R

FIG. 1

FIG. 2

FIG. 3

FIG. 4

FIG. 5

FIG. 1 is a front elevational view of one form of a building showing the new design with the rear (not shown) being plain.

FIG. 2 is a top plan view of the building of FIG. 1.

FIG. 3 is a right side elevational view of the building of FIG. 1.

FIG. 4 is a top plan view of another form of a building showing the new design with its front view being the same as that of FIG. 1 and the rear view (not shown) being plain.

FIG. 5 is a side elevational view of the building of FIG. 4 and the other side (not shown) of the building being identical to FIG. 5.

I claim:

The ornamental design for a building, substantially as shown and described.
